FOLDING PICTURE VIEWING DEVICE

Arthur H. Crapsey, Jr., Rochester, N. Y., assignor to
Eastman Kodak Company, Rochester, N. Y., a corporation of New Jersey

Application May 24, 1954, Serial No. 30,630

Term of patent 14 years

(Cl. D61—1)

Fig. 1

Fig. 2

Fig. 3

Fig. 4

Fig. 5

Fig. 6

Fig. 8

Fig. 7

Fig. 1 is a front elevational view of a folding picture viewing device showing my new design and shown in a folded position;

Fig. 2 is a side elevational view thereof;

Fig. 3 is a rear elevational view thereof;

Fig. 4 is an end elevational view thereof;

Fig. 5 is an end elevational view of the opposite end thereof;

Fig. 6 is a side elevational view thereof shown in an unfolded position;

Fig. 7 is a front elevational view thereof shown in an unfolded position; and

Fig. 8 is a top plan view thereof shown in an unfolded position.

I claim:

The ornamental design for a folding picture viewing device, as shown.
